UNITED STATES PATENT OFFICE.

FRANZ O. MATTHIESSEN, OF IRVINGTON, NEW YORK.

CONTINUOUS FILTER FOR FILTERING SUGAR-LIQUOR.

SPECIFICATION forming part of Letters Patent No. 329,184, dated October 27, 1885.

Application filed May 9, 1885. Serial No. 164,866. (No model.)

To all whom it may concern:

Be it known that I, FRANZ O. MATTHIESSEN, of Irvington, New York, have invented certain Improvements in Continuous Filters for Filtering Sugar-Liquor, of which the following is a specification.

My invention relates to apparatus for effecting the filtration of sugar-liquor through a mass of bone-black, which is being continuously or nearly continuously removed from the place where the sugar-liquor is first introduced into the filter, so that the sugar-liquor is first brought into contact with the more exhausted black, and as it makes its way through the filtering apparatus is brought into contact with bone-black, which is less and less exhausted, and is finally discharged from the filter at or near the place where the fresh bone-black is introduced into the filter.

20 The accompanying drawings, illustrating filtering apparatus embodying my invention, are as follows:

Figure 1 is a top view. Fig. 2 is a central vertical section through the line $x-x$ on Fig. 1. 25 Fig. 3 is a transverse section of the lower portion of the apparatus through the line $y-y$ on Fig. 2.

The apparatus consists of a larger vertical cylinder, A, the lower end of which is provided with a horizontal diaphragm, a , containing a multiplicity of perforations. Immediately beneath the stationary diaphragm a is a revolving disk, a' , provided with perforations capable of being successively brought 30 by the rotation of the disk a' into alignment with the perforations in the stationary diaphragm a . The rotation of the disk a' is effected by means of the horizontal shaft a^2 , provided upon its inner end with the bevel-pinion a^3 , which engages the teeth a^4 , formed upon the under side of the rotating disk a' , and which is driven by a belt which engages the pulley a^5 , affixed to the portion of the shaft a^2 which projects outside of the cylinder A.

40 45 50 The perforations in the stationary diaphragm are arranged in concentric circles of different diameters, and those in the rotating plate are arranged in concentric circles of like diameters, respectively; but the perforations in the rotating disk are so arranged relatively to the perforations in the stationary diaphragm that when the perforations in the middle portions

of the rotating disk are brought into alignment with the corresponding perforations in the middle of the stationary diaphragm the 55 perforations near the periphery of the rotating disk are out of alignment with the perforations near the periphery of the diaphragm, or, vice versa, when the perforations near the periphery of the rotating disk and those near 60 the periphery of the diaphragm are brought into alignment with each other the perforations near the middle of the plate and of the diaphragm are out of alignment with each other. The object of this relative arrangement of the systems of perforations is to effect a uniform discharging movement from all parts of the base of the mass of bone-black A' contained in the cylinder A.

The bone-black discharges through the perforations in the diaphragm a , and the rotating plate a' falls into a chamber, B, the bottom of which is rounded and forms a trough, the lower half of which is concentric with the horizontal screw-propeller shaft C, one end, C', of which 70 projects through the wall of the chamber B, and is provided with a toothed wheel or pulley, by means of which the propeller is rotated. The opposite end of the chamber B communicates, by means of a short tube, B', 75 with the lower end of a vertical elevator cylinder or well, D, containing a vertical elevator-screw, D', the lower end of which is seated in a step, d, formed upon the bottom of the vertical cylinder D.

80 85 A suitable frame extending across the end of the tube B' adjoining the lower end of the cylinder D supports the journal C² for the inner end of the horizontal shaft C.

At the upper end of the cylinder D there is 90 provided the inclined chute E, by means of which the bone-black elevated by the elevator-screw D' is carried off.

The service-pipe F, for conducting the sugar-liquor to be filtered into the filter, is situated 95 at a suitable distance below the chute E.

Near its upper end the wall of the cylinder A is provided with a series of perforations, G, through which the sugar-liquor which has passed through the black is conducted to the 100 trough G', from which it is led into suitable receiving-vessels.

One or more thicknesses of blanket, G², are arranged in connection with the openings G

in the usual manner, to prevent the passage of the bone-black into the trough *g*.

In operation, the bone-black is fed into the upper end of the cylinder *A*, and by means of the adjustable plate *a'* and perforated dia-
5 phragm *a* is discharged into the chamber *B*, along the bottom of which it is propelled by the horizontal propelling-screw *C* into the bottom of the well or elevating-cylinder *D*, up which 10 it is elevated by the rotation of the vertical screw *D'*, and from which it is discharged at the top into the chute *E*. The sugar-liquor fed through the pipe *F* falls by its own gravity down through the black contained in the ele-
15 vator-tube *D*, and rises by hydrostatic pressure in the cylinder *A* and is discharged through the perforations *G* into the trough *g*. The speed of rotation of the propeller-shafts *C* and *D* is regulated with reference to removing the 20 black from the filter as rapidly as it becomes exhausted, so that its place may be taken by fresh bone-black fed into the upper end of the cylinder *A*.

The propelling-screws may be kept in con-
25 tinuous slow rotation, or they may be rotated intermittently, if desired. In either case the substantial result is that the bone-black is fed continuously, or substantially so, through the filtering apparatus in one direction, while the 30 sugar-liquor is fed through the apparatus and through the bone-black in the opposite direction.

The bone-black, as will be seen, moves through one part of the filtering apparatus—
35 to wit, the cylinder *A* and the chamber *B*—by its own gravity, and is moved through the remaining portion of the apparatus by me-
chanical means.

I claim as my invention--

1. In apparatus for filtering sugar-liquor 40 through bone-black, a vertical cylinder, into the top of which bone-black is fed, and down which it falls by its own gravity, a receiving-chamber at the bottom of said vertical cylinder, and an elevator-tube connected with the 45 said receiving-chamber, and means for moving the bone-black from the receiving-chamber and thence upward through the elevator-tube, and discharging it at or near the top of the elevator-tube, in combination with a service- 50 pipe for introducing the sugar-liquor into the upper part of the elevator-cylinder, and a discharge outlet or outlets for the discharge of the sugar-liquor from the apparatus, the arrangement being such that the mass of bone- 55 black is moved through the filtering apparatus in one direction, while the sugar-liquor is moved through it or through a suitable part of it in the opposite direction, substantially as described.

2. The combination, with the bone-black filter, of an upright elevator-cylinder provided with an elevator-screw, the axis of which is coincident with the axis of the said cylinder, for elevating bone-black through said cylinder and discharging it from the top thereof, and means for conveying the exhausted bone- 65 black from the bottom of the filtering-chamber to the lower part of said cylinder, substantially as and for the purpose set forth.

F. O. MATTHIESSEN.
